US0D1100913S

(12) **United States Design Patent** (10) **Patent No.:** **US D1,100,913 S**
(45) **Date of Patent:** **** Nov. 4, 2025**

(54) **TABLET CASE**

(71) Applicant: **Electronic Silk Road (Shenzhen) Tech Co., Ltd.**, Guangdong (CN)

(72) Inventors: **Yuchen Qiu**, Guangdong (CN); **Zhigang Xia**, Guangdong (CN)

(73) Assignee: **Electronic Silk Road (Shenzhen) Tech Co., Ltd.**, Shenzhen (CN)

(**) Term: **15 Years**

(21) Appl. No.: **29/944,181**

(22) Filed: **May 27, 2024**

Related U.S. Application Data

(63) Continuation-in-part of application No. 35/517,549, filed on Feb. 22, 2023 (U.S. filing date under 35 U.S.C. 384), and having an international filing date of Feb. 22, 2023, now abandoned.

(57) **CLAIM**

The ornamental design for a tablet case as shown and described.

DESCRIPTION

FIG. 1 is a top, front and right side perspective view of a tablet case showing our new design;

FIG. 2 is a bottom, rear and left side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 2;

FIG. 11 is a top, rear and left side perspective view showing the tablet case in a state of use; and,

FIG. 12 is a top, rear and left side perspective view showing the tablet case in another state of use.

The evenly dashed broken lines in the drawings illustrate portions of the tablet case which form no part of the claimed design.

The dot-dashed broken lines illustrate the boundary of the enlarged view and form no part of the claimed design.

1 Claim, 12 Drawing Sheets
